HERMANN KRÜGER, OF HOLZEN, NEAR SCHWERTE, GERMANY.

BLADE-ATTACHING MEANS.

No. 921,547.

Specification of Letters Patent.

Patented May 11, 1909.

Application filed December 12, 1908. Serial No. 467,190.

To all whom it may concern:

Be it known that I, HERMANN KRÜGER, merchant, subject of the German Emperor, residing at Holzen, near Schwerte, in Westphalia, Empire of Germany, have invented new and useful Improvements in or Relating to Blade-Attaching Means, of which the following is a specification.

The present invention relates to knives and other implements and particularly to table-knives, and an important object is to provide improved means for attaching knife-blades and the like in metal hafts.

As is known, knife-blades have heretofore been fastened in metal hafts almost exclusively by means of solder or cement. Apart from the troublesomeness of securing them in this manner, this mode of attachment has the disadvantages that it always makes the knife very heavy and when in use the blades frequently gradually become loose.

An important object of the invention is to do away with these defects.

Now the present invention is based on the fact that the blade of a knife is not loosened and detached owing to tensions in the blade, but on the contrary owing to the forces which continually recur in use tending to turn the knife-blade around the longitudinal axis of the knife; therefore when providing means for attaching the blade to the haft particular care must be taken that the means of attachment are able to oppose effective resistance to just these forces. With this end in view, in accordance with the present invention the tang is made as a strong, short, slightly tapering pin of optional polygonal, quadrangular, triangular, flat parallelogrammatic, circular, elliptical or like form, and a strong plate is attached in the haft at a distance from the upper end of the haft almost equal to the length of the tang; this plate has in it a hole corresponding in shape exactly or only approximately with the cross-section of the tang, but rather smaller than the end of the tang, so that very great pressure is required to press the wedge-like end of a quadrangular tang so far into a quadrangular hole, and still more pressure to press a hexagonal tang for example into the circular hole in the plate in the haft that the bolster of the knife-blade is correctly placed with regard to the haft. Consequently it is not at all necessary for the shape of the hole in the plate attached in the haft to correspond exactly with the shape of the cross-

section of the tang, but when the tang is hexagonal, for example, the hole may very well be circular, and when the tang is a flat parallelogram in shape, the hole may be elliptical, and vice versa. In these cases it also depends on the hole in the plate being somewhat too small for the tang to be readily inserted therein. In this manner the strength of the attachment is considerably increased, since the edges of the tang are embedded deeply into the sides of the hole in the plate and become firmly held there, the faces of the hole and tang are deformed and engage one another.

Owing to a wedge-shaped tang being exceedingly powerfully clamped and simultaneously engaged in the more or less exactly fitting hole in the plate, the connection between the haft and blade is made so firm and secure that it is quite impossible for the blade to be loosened by the normal forces which tend to twist the latter in the haft. But also an exceedingly firm connection between the blade and haft is obtained in an axial direction by means of the tang being compressed firmly in the hole in the plate when it is driven into the latter, in consequence of the wedge-shaped form of the tang which is rather too large for the hole. In order to oppose the twisting forces in like manner, in addition to the above arrangement the bolster of the blade is let into the end of the haft projecting beyond the plate, whereby these forces are effectively transmitted from the head of the blade directly to the haft, and it is quite impossible for the tang to bend.

In order that the invention may be clearly understood reference will be made to the accompanying drawing wherein several embodiments are represented by way of example, and wherein:

Figure 1 is a side elevation of a table-knife showing the haft with the blade attached therein, a part of the haft being shown in section, and Fig. 2 is a cross-section in the plane 2—2 in Fig. 1. Fig. 3 is a cross-section of a regular hexagonal tang pressed into a circular hole in a haft, Fig. 4 is a like view of a quadrangular tang in an elliptical hole, and Fig. 5 is a like view of a parallelogrammatic tang in an elliptical hole, whereas Fig. 6 is a like view of a round tang in a regular hexagonal hole.

Referring to the drawing, and firstly particularly to Figs. 1 and 2, the plate *p* having

in its center a quadrangular hole is attached by soldering or other suitable manner in the upper portion of the metal haft *h* directly below the constriction *i* at the head of the blade *b*. The square tang *e* is only just so long that its end projects a very little out of the plate after it has been pressed into the square hole in the same, and the end is slightly tapered and, compared with the hole in the 10 plate, so large that after the tang has been mechanically forced into the hole like a wedge, the faces of the tang and hole are pressed against one another with great pressure. As tests have shown, the connection 15 made in this manner can only be broken by an axial tension due to a weight of 300 to 400 kilograms. An additional hold of the blade and protection against its turning in the haft is obtained at the joint between the 20 bolster *k* and the upper edge of the haft. Namely the bolster *k* and the end of the haft *h* preferably likewise just barely fit one in the other and are pressed together. Also, in addition, some solder may be run into the joint 25 between the haft and the bolster, for the purpose of securing the blade still more firmly, and in order at the same time to prevent dirt settling in this joint and water penetrating into the metal haft. Also when making the 30 attachment a few drops of solder can be dropped onto the end of the tang before it is pressed into place, but this is by no means necessary for obtaining a firm joint.

In Figs. 3 to 6 a number of other tangs of 35 various shapes are shown pressed into holes in plates in the haft; the shapes of the holes being different from those of their respective tangs, as described above.

It is of no importance if the tang and hole

in the plate, which are reciprocally deformed when the joint is made, do not contact at all parts. The gaps which there may be may, however, be filled up by some drops of solder which can be applied when the tang is being pressed into the plate, as already mentioned.

It is to be understood that the tang and hole in the plate, as well as the bolster and the appertaining part of the haft can be constructed in other like or different forms without departing from the spirit and scope of the invention. It is also to be understood that although the invention has been described with reference to table-knives, any other operative part of an implement or tool may be attached in its metal haft in like manner, without departing from the spirit and scope of the invention.

What I claim as my invention and desire to secure by Letters Patent is:

In a tool or implement, the combination 60 with the hollow metal haft having a constriction adjacent its inner end, a plate secured in the haft below the constriction, said plate having a hole therein, the operating part of the tool having a tang at its end, said 65 tang being of larger diameter than the hole and forced therein, and a bolster *k* on the operating part of the tool, said bolster being secured in the end of the haft above the constriction.

In testimony whereof I have signed my name to this specification in the presence of two subscribing witnesses.

HERMANN KRÜGER. [L. S.]
